HOME BAR OR SIMILAR ARTICLE

Harry R. Greenberg, Lake Success, N. Y.

Application July 19, 1957, Serial No. 46,994

Term of patent 14 years

(Cl. D33—19)

Fig. 1 is a front perspective view of a home bar showing my design;

Fig. 2 is a rear elevational view; and

Fig. 3 is a side elevation view thereof.

The characteristic features of my design reside in the combination on the bar disclosed of the bifurcated body in association with the scalloped base and rectangular top as shown in full lines.

I claim:

The ornamental design for a home bar or similar article, as shown and described.
